UNITED STATES PATENT OFFICE.

EARL H. SHERBONDY, OF CLEVELAND, OHIO, ASSIGNOR, BY MESNE ASSIGNMENTS, TO
THE FRANTZ PREMIER CO., OF CLEVELAND, OHIO.

WASHING-MACHINE.

1,292,525.

Specification of Letters Patent. Patented Jan. 28, 1919.

Application filed May 26, 1916. Serial No. 100,018.

To all whom it may concern:

Be it known that I, EARL H. SHERBONDY, a citizen of the United States, and a resident of Cleveland, county of Cuyahoga, and 5 State of Ohio, have invented a new and useful Improvement in Washing-Machines, of which the following is a specification, the principle of the invention being herein explained and the best mode in which I have 10 contemplated applying that principle, so as to distinguish it from other inventions.

The present improvements, relating as indicated to washing machines, have more particular regard to a mechanism for this particular 15 pose which is self-contained and which can be used in conjunction with an ordinary wash-tub or other suitable receptacle for clothes. Another object of the invention is to provide a machine of this character which 20 can be adjusted to various sizes of receptacles and which can be inexpensively manufactured and conveniently used. To the accomplishment of the foregoing and related ends, said invention, then, consists of the 25 means hereinafter fully described and particularly pointed out in the claims.

The annexed drawing and the following description set forth in detail certain mechanism embodying the invention, such disclosed 30 means constituting, however, but one of various mechanical forms in which the principle of the invention may be used.

In said annexed drawing:—

Figure 1 is a central longitudinal section 35 of the device, some parts being shown in elevation; Fig. 2 is a side elevation of the device mounted in position upon a receptacle; Fig. 3 is a section on the line 3—3 in Fig. 1; Fig. 4 is a central vertical section on an enlarged 40 scale of a portion of the reciprocating mechanism; Fig. 5 is a section on the line 5—5 in Fig. 4; and Fig. 6 is a plan view showing a detail of construction.

It is highly desirable, in a machine of the 45 present character, to be able to use a small high-speed motor, preferably electrical, since such a motor can be built at a relatively low expense, and the weight of the same will of course be very much less than 50 if a larger slow-speed motor were used. It is necessary, in case a small high-speed motor is employed, to provide means for gearing it down to a relatively slow speed of movement for the plunger, and yet this 55 plunger must have a comparatively long

stroke in order to secure a considerable movement through the fluid in the receptacle. The present machine has been particularly designed with these objects in view.

Referring now to Figs. 1 and 2, there is 60 shown a casing 1 in which is inclosed the motor, this casing being securely bolted to a larger flared casing 2 in which is mounted the operating mechanism for the plunger, and through the bottom 3 of which extends 65 the plunger 4, the latter being provided at its lower end with vacuum cups 5. Around the lower edge of the casing 2 there is mounted a ring 6 adapted to be engaged by clamps 7 on the upper end of 70 extensible arms or supports which are provided on their lower ends with other clamps 8 adapted to engage the edges of the receptacle. Preferably three or more of these clamps will be used, and as shown in Fig. 1 75 each clamp will consist of a tube 9 slidably receiving therein a rod 10, thus rendering it possible to shorten or lengthen these supports as desired, the tube and rod being clamped in any desired relative position by 80 means of winged set-screws 11 or some similar means. In order to accommodate the machine to receptacles of different shapes, it is possible to loosen the clamps 7 and move the supports to any desired points about the 85 ring 6.

Connected to the armature of the motor is a shaft 12 extending vertically and centrally through the casing 2 and having mounted thereon a fly-wheel in the form of 90 disks 13 and 14 which are clamped together by means of bolts. The disks 13 and 14 serve not only as a fly-wheel but also as a clutch for connecting the armature to the shaft 12. On the shaft 12 there is formed 95 a worm 15 driving two worm wheels 16 and 17 (see Fig. 3), these worm wheels being rotatably supported upon studs or shafts 18 which are screwed into inward extensions 19 and 20 from the partition 26. These 100 extensions 19 and 20 are disposed on opposite sides of the center plane of the worm wheels, and in this way the worm wheels are evenly balanced about the central vertical axis of the mechanism. Attached to the worm wheels 16 and 17, on opposite sides thereof, are eccentric pins 21 to which are attached rods 22 extending downward and serving as cranks to operate link mechanism consisting of the pivotally connected 110

rods 24 and 25, the upper end of the rod 24 being supported upon a partition 26 extending across the casing at this point, and the lower ends of the rod 25 being connected to a collar 27, which in turn is connected to the reciprocable plunger 4. It will be readily seen that operation of the motor will rotate the shaft 12, thus turning the worm wheels 16 and 17 and simultaneously operating the cranks 22, in this way alternately raising and lowering the collar 27 and the plunger 4.

It is desirable to slowly rotate the plunger 4 as well as to reciprocate the same, and mechanism for this purpose is provided and is shown in Figs. 1 and 5. This mechanism, which may take various forms, is here shown as consisting of a rod 30 having therein a slot 31 engaging over a pin 32 attached to one of the links 25. This rod 30 is attached to a collar 33 mounted about the tube 4 and bearing a pawl 35 normally held in engagement with a ratchet wheel 36 attached to the tube 4 by means of a spring 37. The movement of the rod 25 picks up the rod 30 and moves it sufficiently to cause the pawl 35 to turn the ratchet wheel, and with it the tube 4, one notch upon each full stroke of the plunger, so that the plunger is rotated through one revolution for about every twenty-five strokes up and down. It will be evident that any other means might be used to secure this same indexing movement of the plunger, and the plunger may be moved other distances around for each reciprocation.

Other modes of applying the principle of my invention may be employed instead of the one explained, change being made as regards the mechanism herein disclosed,

provided the means stated by any of the following claims or the equivalent of such stated means be employed.

I therefore particularly point out and distinctly claim as my invention:—

1. In a washing machine, the combination of a casing, washing apparatus mounted therein and adapted to extend into a receptacle, a plurality of extensible supports pivotally attached to said casing and provided with means adapted to engage the sides of a receptacle and support said casing thereon.

2. In a washing machine, the combination of a casing, washing apparatus mounted therein and adapted to extend into a receptacle, a plurality of extensible supports pivotally attached to said casing and provided with pivotally attached clamps adapted to engage the sides of a receptacle and support said casing thereon.

3. In a washing machine, the combination of a casing, washing apparatus mounted therein and adapted to extend into a receptacle, means for adjustably supporting said casing and apparatus above a receptacle, said means consisting of a plurality of extensible supporting tubes, means for holding them in desired relation, one end of each of said tubes being pivotally attached to said casing, clamps for maintaining them in desired angular position with respect to said casing, and other clamps pivotally attached to the lower ends of said tubes and adapted to engage with the sides of the receptacles.

Signed by me, this 11th day of May, 1916.

EARL H. SHERBONDY.
